COMPRESSOR UNLOADING MECHANISM

Paul Diserens, Summit, N. J., assignor to Washington Pump and Machinery Corporation, Harrison, N. J., a corporation of Delaware

Application January 3, 1942, Serial No. 425,522

7 Claims. (Cl. 230—29)

This invention relates to compressors and more particularly to compressor loading and unloading means.

An object of the invention is to provide an unloading mechanism of the start and stop type for compressors which will unload the compressor upon its stopping and maintain it in unloaded condition after it has started until it has picked up speed, thereby minimizing the load on the prime mover of the compressor during starting periods of operation.

Another object of the invention is the provision of a stop and start unloader for compressors which utilizes a combination of centrifugal force and hydraulic clutch action for operating a valve to control the loading and unloading of the compressor.

A further object of the present invention is to provide a compressor unloading mechanism in which mechanical friction in the unloading valve operating means is eliminated.

More specifically, the present invention comprehends an unloading mechanism in which a hydraulic clutch of the "Foettinger" type is employed as a coupling medium between the compressor driving shaft and the unloading mechanism whereby the unloading mechanism will not be operated to load the compressor until the compressor has reached a speed, upon starting, sufficient to initiate coupled operation between the driving and driven parts of the hydraulic coupling.

With these and other objects in view, as may appear from the accompanying specification, the invention consists of various features of construction and combination of parts, which will be first described in connection with the accompanying drawings, showing a compressor unloading mechanism of the preferred form embodying the invention, and the features forming the invention will be specifically pointed out in the claims.

In the drawings:

Figure 1 is a vertical section through a compressor equipped with the improved unloading mechanism.

Figure 2 is an enlarged longitudinal section through the unloading mechanism.

Figure 3 is a vertical section taken on the line 3—3 of Figure 2.

Figure 4 is a vertical section taken on the line 4—4 of Figure 2.

Figure 5 is a vertical section taken on the line 5—5 of Figure 2.

Referring more particularly to the drawings, I

indicates a compressor of any approved type embodying a compressing piston 2, operated by the driving shaft 3. The driving shaft 3 is driven from any suitable type of prime mover (not shown), and the fluid compressed by the compressor is discharged through the discharge from the compression space 4 through the connection 4'.

For the purpose of unloading the compressor, 10 upon starting, to relieve the prime mover of starting stresses, a pipe 5 is connected to the discharge line 4' between the compressor and the check valve 6, and this unloading pipe 5 opens into a valve housing 7, which latter is provided with ports 8 opening to atmosphere. The ports 8 are controlled by a valve piston 9, mounted for reciprocating movement within the housing 7. When the valve 9 is seated against the valve seat 10, the ports 8 are closed and communication 15 between the compression space 4 of the compressor and the atmosphere, through the pipe 5 and discharge line 4', is shut off, at which time the compressor will operate in loaded condition. When the valve 9 is in its lowered position, as 20 shown in Figure 2 of the drawings, the ports 8 are open and consequently the discharge line 4' and compression space 4 will be open to atmosphere, permitting operation of the compressor in an unloaded condition.

25 The valve piston 9 has a valve stem 11 connected thereto which projects into the housing 12 containing the mechanism for operating the valve 9. The valve stem 11 has a head 14 on its inner or lower end, which head 14 is held in engagement with the peripheral surface of a cam 15 by means of a spring 16. The spring 16 is engaged at its end opposite to the head 14 by a spring tensioning nut 17, and the tension of the spring may be regulated by adjustment of 30 said nut 17.

35 The cam 15 is rotatably mounted upon a shaft extension 18 connected to the driving shaft 3 of the compressor in any suitable manner. A sleeve 19, either formed integrally with or fixedly connected to the cam 15, and has the driven impeller structure 20 of the hydraulic coupling structure 21 mounted thereon. The hydraulic coupling or clutch structure 21 is of the simple "Foettinger" type, comprising a driving element 22, direct connected to the driving shaft 3 of the compressor for rotation therewith, and the driven element 20, in conjunction with the housing 26. The vanes 24 of the driving element 22 and the vanes 25 of the driven element 20 are enclosed within said coupling hous-

ing 26, which latter is open, by means of ports 21, to the interior of the housing 12. The housing 12 is open to the lubricating system of the compressor through a suitable port or ports 28, so that a part of the oil from the lubricating system of the compressor will flow into the interior of the housing 12, at least partially filling it, and thence into the interior of the clutch housing 26 through the said ports 21.

When the compressor is started, the blades or vanes 24 of the driving element 22 will act upon the oil in the housing 26 and when the centrifugal force upon the oil developed by said driving impeller structure 22 reaches a degree sufficient to overcome the tension of the spring 16 as exerted against the cam 15 through the medium of the head 14, a coupled condition will exist between the driving element 22 and the driven element 20 of the hydraulic clutch structure 21, and since the driven element 20 is connected to the cam 15, the cam will be rotated in a counterclockwise direction. The head 14 of the valve stem 11, riding upon the surface of the cam 15, will cause an outward or upward movement of the valve stem 11 and the valve 9, moving the valve 9 into position upon its seat 10 and closing the ports 8, cutting off communication between the pipe 5 and atmosphere. Thus, during the continued operation of the compressor, it will be in a loaded condition.

The cam 15 has a stop 30 formed on its periphery, and when the cam has moved a sufficient distance to seat the valve 9, further rotation of the cam will be arrested through engagement of the head 14 of the stem 11 against said stop 30. At such time the hydraulic clutch will in effect "slip" and continued seating and unseating of the valve 9, such as would be occasioned if the cam 15 were allowed to continue rotating during operation of the compressor, will be prevented, but the centrifugal force exerted against the vanes 25 of the driven element 20 through the medium of the oil being acted upon by the driving element 22, will be sufficient to maintain the cam 15 in its valve seating position.

When the compressor is stopped, the coupled relation between the driving element 22 and the driven element 20 of the hydraulic clutch structure 21 will of course be broken and the cam 15 will be moved in a clockwise direction through the medium of the counterweight 31 attached thereto, and the head 14 of the stem 11, following the peripheral surface of the cam 15, will permit the valve 9 to be moved downwardly, under action of the spring 16, to open the ports 8 to atmosphere and thus unload the compressor. The movement of the cam 15 in such clockwise direction into valve unseating position is limited by means of the stop 32 formed on the periphery of the cam.

By varying the tension of the spring 16 the time delay before loading of the compressor, upon starting, may be varied; or, the operating speed required before loading of the compressor may be varied, since by adjustment of the tension of the spring 16 variation of the power, developed through the hydraulic clutch structure 21 as driven by the shaft 3, required to move the cam 15 into position for loading the compressor is provided. In other words, by increasing the tension of the head 14 against the surface of the cam 15, a higher speed of the shaft 3 is required for developing the power required for moving or rotating said cam.

While the cam 15 is returned to compressor unloading position by means of the counterweight

31 in the structure shown in the drawings, it is to be understood that any other suitable means may be employed for returning the cam to its compressor unloading position, without departing from the spirit of the present invention.

In the drawings and in the foregoing description, the hydraulic coupling 21 and the valve unloading mechanism is shown as connected to the operating shaft of the compressor, but it is to be understood that in instances where the construction of the compressor and its prime mover are such as to warrant, the hydraulic coupling and its companion mechanism may be mounted or otherwise suitably connected to the driving shaft of the prime mover.

It will be understood that the invention is not to be limited to the specific construction or arrangement of parts shown, but that they may be widely modified within the invention defined by the claims.

What is claimed is:

1. In an unloader for compressors, the combination of a compressor including a compression space, an operating shaft for the compressor, and a lubricating system, a valve housing having a passage open to said compression space and to atmosphere to permit unloading of the compressor, a valve in said housing seated to close said passage to atmosphere to load the compressor and unseated when the compressor is not operating to unload the compressor, a cam for seating said valve and holding it in seated position, a hydraulic coupling comprising driving and driven parts connecting said cam and operating shaft whereby when the operating shaft reaches sufficient speed of rotation to set up coupled connection of said driving and driven parts of the hydraulic coupling the valve will be seated to load the compressor, means connecting said hydraulic coupling to said lubricating system whereby the hydraulic coupling will receive operating oil from the lubricating system, and tensioned means cooperating with the cam for applying tension to the cam to control the operation of the cam by said hydraulic coupling.

2. In an unloader for compressors, the combination of a compressor including a compression space, an operating shaft for the compressor, and a lubricating system, a valve housing having a passage open to said compression space and to atmosphere to permit unloading of the compressor, a valve in said housing seated to close said passage to atmosphere to load the compressor and unseated when the compressor is not operating to unload the compressor, a cam for seating said valve and holding it in seated position, a hydraulic coupling comprising driving and driven parts connecting said cam and operating shaft whereby when the operating shaft reaches sufficient speed of rotation to set up coupled connection of said driving and driven parts of the hydraulic coupling the valve will be seated to load the compressor, means connecting said hydraulic coupling to said lubricating system whereby the hydraulic coupling will receive operating fluid from the lubricating system, tensioned means cooperating with the cam for applying tension to the cam to control the operation of the cam by said hydraulic coupling, and adjustable means for regulating the tension of said tensioning means for regulating the pressure developed by said hydraulic coupling required for operating said cam.

3. In an unloader for compressors, the combination with a compressor including an operat-

ing shaft and a compression space, and a lubricating system, of a valve housing having a passage open to said compression space and to atmosphere to permit unloading of the compressor, a valve in said housing seated to close said passage to atmosphere to load the compressor and unseated when the compressor is not operating to unload the compressor, a cam for seating said valve and holding it in seated position, a hydraulic coupling comprising driving and driven parts connecting said cam and operating shaft whereby when the operating shaft reaches sufficient speed of rotation to set up coupled connection of said driving and driven parts of the hydraulic coupling the valve will be seated to load the compressor, means connecting said hydraulic coupling to said lubricating system whereby the hydraulic coupling will receive operating fluid from the lubricating system, tensioned means cooperating with the cam for applying tension to the cam to control the operation of the cam by said hydraulic coupling, adjustable means for regulating the tension of said tensioning means for regulating the pressure developed by said hydraulic coupling required for operating said cam, means associated with said cam for operating the cam to permit unseating of the valve upon breaking of the coupled connection between the driving and driven parts of the coupling, a stop on said cam for arresting movement of the cam when the valve is fully seated and a second stop on said cam for arresting movement of the cam when the valve is in fully unseated position.

4. In an unloader for compressors, the combination with a compressor including an operating shaft and a compression space, and a lubricating system, of a valve housing having a passage open to said compression space and to atmosphere to permit unloading of the compressor, a valve in said housing seated to close said passage to atmosphere to load the compressor and unseated when the compressor is not operating to unload the compressor, a cam for seating said valve and holding it in seated position, a hydraulic coupling comprising driving and driven parts connecting said cam and operating shaft whereby when the operating shaft reaches sufficient speed of rotation to set up coupled connection of said driving and driven parts of the hydraulic coupling the valve will be seated to load the compressor, means connecting said hydraulic coupling to said lubricating system whereby the hydraulic coupling will receive operating fluid from the lubricating system, a spring for applying pressure to said cam to regulate the degree 55

of pressure required for rotating the cam to seat said valve, and adjustable means for regulating the tension of said spring to provide regulation of the degree of pressure required to rotate the cam into valve seating position.

5. In an unloader for compressors, the combination with a compressor including an operating shaft, a compression space and a lubricating system, of a valve structure open to said compression space and constructed and arranged to load the compressor when seated and unload the compressor when unseated, means for operating said valve structure, a housing connected to said compressor and being open to the lubricating system of the compressor for receiving oil therein, a hydraulic coupling in said housing connected to and operated by said operating shaft, said hydraulic coupling being provided with openings to receive therein oil from said housing, and means connecting said hydraulic coupling to said valve structure operating means.

6. In an unloader for compressors, the combination with a compressor including a compression space, an operating shaft and a lubricating system, of a valve structure having communication with said compression space to unload the compressor when the valve is open and load the compressor when the valve is closed, a hydraulic coupling comprising driving and driven parts, 30 said driving parts connected to said operating shaft for operation thereby, means connected to said driven part and operated thereby for operating said valve, a housing about said hydraulic coupling and provided with means for receiving oil from the lubricating system of the compressor, said hydraulic coupling provided with ports to permit ingress of oil thereinto from said housing, and means for applying tension to said driven member.

7. In an unloader for compressors, the combination with a compressor including an operating shaft, a compression space, and a lubricating system, of a valve structure open to said compression space and constructed and arranged to load the compressor when seated and unload the compressor when unseated, means for operating said valve structure, a hydraulic coupling connected to and operated by said operating shaft, means connecting said hydraulic coupling and said lubricating system whereby the hydraulic coupling will receive operating fluid from the lubricating system, and means connecting said hydraulic coupling to said valve structure operating means.

PAUL DISERENS.
